James O'Shaughnessy INVENTOR
BY ATTORNEY

Stan E. O. Koenigberg

UNITED STATES PATENT OFFICE

JAMES O'SHAUGHNESSY, OF TUCKAHOE, NEW YORK

WRITING IMPLEMENT

Application filed February 19, 1931. Serial No. 516,874.

The object of this invention is to provide a novel and improved inkstand and fountain pen having cooperating means whereby the self filling mechanism of a self filling fountain pen is automatically operated so that the pen will be filled each time it is dipped into the ink in the inkstand. Another object is to improve the self filling pen mechanism so that it will cooperate with the inkstand for automatic self filling purposes. Other objects will appear as this specification proceeds. In the accompanying drawings illustrating the invention.

Figure 1 is a view, partly in section and partly in elevation, with parts broken away, of an inkstand and fountain pen embodying the invention.

Figures 2 and 3 are detail views of parts of the fountain pen.

Referring to Figure 1 the reference numeral 5 denotes the inkstand which may be of any size, shape and material. Preferably it will be in the form of a suitable base member having a sloping bottom 6 and a centrally disposed threaded opening 7 in the top. A separate filling opening, not shown, may be provided. Into the opening 7 there is screwed a pen guiding and operating member which is hollow and preferably formed 30 with a threaded base 8, adapted to be screwed into the opening 7, and an inclined neck or stem 9 having a flaring mouth forming an interior annular cam surface 10.

The self filling fountain pen is indicated at 35 12 and is of any usual or standard construction except as hereinafter noted.

The pen is identified by its main component parts namely the barrel 12, the pen point 13, the rubber bag 14, the deflating spring 15 and the spring operating lever 16. These parts may all be constructed in the manner well known in the art, except that the spring operating lever 16 is shaped in a novel manner to co-operate with the cam 10 in the ink- 45 stand.

The lever 16 is provided with a wedge shaped or tapered abutment 17 to one side of the pivot 18 and the arm 19 of the lever may desirably be made quite substantial or thickened somewhat in comparison with the usual

rather thin operating levers used on self filling fountain pens.

The lever 16 is shaped so that when the pen is inserted into the stem 9, to be dipped into the ink indicated at 20, the abutment 17 slides against and engages the annular cam 10 whereby said abutment is pushed inwardly and operated to depress the spring 15 and deflate the rubber bag 14 in the usual manner. The lever 16 is further so shaped and proportioned that as the pen 13 is dipped into the ink, the arm 19 is tipped outwardly and also engages the cam 10 thereby coming to a fixed position as shown in Figure 1 from which it will be seen that the lever also acts as a stop for the insertion of the pen, the cam 10 engaging the lever at two points to wedge or stop the pen, as it were in self filling position.

The parts are so arranged and proportioned that the user merely dips the pen into the inkstand until the movement is arrested by the engagement of the lever 16 with the sides of the guiding neck 9, at which time the pen will have been dipped into the ink.

Upon withdrawing the pen, the rubber bag will become inflated at once and the pen will be filled with ink sufficient for ordinary usage. When it is desired to use the pen independently of the inkstand for any length of time, it may of course be filled in the usual manner.

It will further be understood that details of construction, the shape and form of the inkstand and the like may be changed without departing from the principle of the invention. The sloping bottom of the inkstand insures a reasonable supply of ink being always available for filling the pen for ordinary use.

I claim:

1. In combination, a self filling fountain pen having a lever for actuating the self filling mechanism of said pen, an inkstand and means on the latter adapted to operate said lever when the pen is inserted into the inkstand to fill the pen.

2. In combination, a self filling fountain pen having a lever for actuating the self filling mechanism of said pen, an inkstand

and a cam on the latter adapted to engage said lever to operate the same when the pen is inserted into the inkstand to fill the pen.

3. In combination, a self filling fountain pen having a lever for actuating the self filling mechanism of said pen, a projecting abutment formed on said lever, an inkstand, a member on said inkstand through which the pen is adapted to be inserted into the inkstand, said member having an annular cam surface formed thereon and adapted to engage said lever abutment to operate the latter when the pen is inserted into the inkstand for filling the pen.
- 15 4. In combination, a self filling fountain pen having a lever for actuating the self filling mechanism of said pen, a projecting abutment formed on said lever, an inkstand, a member on said inkstand through which the pen is adapted to be inserted into the inkstand, said member having an annular cam surface formed thereon and adapted to engage said lever abutment to operate the latter when the pen is inserted into the inkstand for filling the pen, said lever and cam cooperating to arrest the movement of the pen into the inkstand.
- 30 5. In combination, a self filling fountain pen having a lever for actuating the self filling mechanism of said pen, said lever being pivoted intermediate its end and provided with an abutment to one side of its pivot, an inkstand, a sleeve formed member thereon through which the pen is adapted to be inserted into the inkstand, said member being provided with an annular cam surface at its upper end for engagement with the abutment on the lever to actuate the same and for engagement with said lever to arrest the movement of the pen into the inkstand.
- 35 6. In combination, a self filling fountain pen having a lever for actuating the self filling mechanism of said pen, an inkstand, a sleeve formed member on said inkstand through which the pen is to be inserted to fill the same, an annular cam formed at the entrance of said sleeve formed member and adapted to engage and operate the said lever to actuate the self filling mechanism and limit the movement of the pen into the inkstand.

JAMES O'SHAUGHNESSY.
